Harry C. Wentz, Jr., St. Louis, Mo., assignor to
Central Hood and Container Corporation, St.
Louis, Mo., a corporation of Missouri

Application May 7, 1947, Serial No 138,888

Term of patent 14 years

(Cl. D58—26)

To all whom it may concern:

Be it known that I, Harry C. Wentz, Jr., a citizen of the United States and a resident of the city of St. Louis and State of Missouri, have invented a new, original, and ornamental Design for a Preformed Bottle Hood, of which the following is a specification, reference being had to the accompanying drawing, forming part thereof.

Fig. 1 is a top plan view of a preformed bottle hood, showing my new design.

Fig. 2 is a side elevational view thereof,

Fig. 3 is a bottom plan view thereof; and

Fig. 4 is an enlarged cross-sectional view on the line 4—4 in Fig. 1.

I claim:

The ornamental design for a preformed bottle hood, substantially as shown.

HARRY C. WENTZ, JR.
